UNITED STATES PATENT OFFICE.

FRANK BROOKS AND ISAAC K. HISEY, OF CARLTON, OREGON.

BOTTLE-WASHER.

1,056,774.

Specification of Letters Patent. Patented Mar. 25, 1913.

Application filed May 21, 1912. Serial No. 698,764.

To all whom it may concern:

Be it known that we, FRANK BROOKS and ISAAC K. HISEY, citizens of the United States, residing at Carlton, in the county of Yamhill and State of Oregon, have invented certain new and useful Improvements in Bottle-Washers, of which the following is a specification, reference being had therein to the accompanying drawing.

10 This invention relates to washing devices and has special reference to a device for washing bottles.

15 The principal object of the invention is to provide an improved form of device of this character arranged to wash a number of bottles at the same time.

20 Another object of the invention is to provide an improved form of washer supplied with hot and cold water so arranged that the water may be gradually changed from cold to hot and back again while the device is being operated.

25 With the above and other objects in view, the invention consists in general of certain novel constructions, combinations and arrangements of parts, as will be hereinafter fully described illustrated in the accompanying drawings, and specifically claimed.

30 In the accompanying drawings, like characters of reference indicate like parts in the several views, and Figure 1 is a side elevation partly broken away of a device constructed in accordance with this invention. Fig. 2 is a section on the line 2-2, Fig. 1. 35 Fig. 3 is a vertical median section through the device. Fig. 4 is a detail view showing the valve controlling device.

40 The invention in its present embodiment comprises a stand 10 which supports a drip pan 11 above which is carried a bottle box 12 provided with a series of compartments by means of partitions 13, which compartments are of proper size to receive a bottle. Each of the compartments is provided with 45 a bottom 14 having a centrally disposed opening 15 therein.

45 Extending transversely across the base or support 10 are a series of shafts 16 which are geared together by means of gears 17. 50 Each of the shafts 16 carries, beneath the drip pan, a series of beveled gears 18, the gears on the center shaft preferably facing in the opposite direction to the gears on the outside shaft for the purpose of making the device more compact. Extending beneath the shafts in a direction at right angles

thereto are a series of pipes 19 and the intersections of the pipes and shafts lie immediately beneath the centers of the openings 15. One end of each of the pipes 19 is 60 plugged as at 20 while the other ends of these pipes are connected to a header 21 from the center of which extends a pipe 22. In the pipe 22 is a valve 23. The pipe 22 is connected to a cold water supply pipe 24 65 and a hot water supply pipe 25. These pipes are each separately provided with a valve 26 the handles whereof are connected by means of a bar 27.

Extending across the front of the machine 70 is a shaft 28 whereon is a gear 29 provided with a crank handle 30, the gear meshing with one of the gears 17. This shaft 28 is threaded as at 31 and on this threaded portion is a nut 32 carrying an arm 33 which 75 is slotted as at 34 adjacent its outer end. This slot 34 engages a pin 35 on the bar 27 so that as the shaft 28 is rotated the nut 32 will travel in one direction or the other.

In Fig. 4, the parts are shown with the 80 handles or valve operating arms in the position assumed when the cold water valve in the pipe 24 is closed and the valve 26 of the pipe 25 open. In the dotted lined position the arms are shown in the position 85 assumed when closed. It will be obvious that as the hand wheel is rotated to the right in Fig. 2 the cold water valve will slowly close while the hot water valve will slowly open until full movement is accomplished when the reverse movement will again turn on the cold water. The object 90 of this gradual change is to avoid cracking the bottles.

Extending upward through each of the 95 openings 15 is a pipe 36 which has its lower end connected to one of the pipes 19. Surrounding each of these pipes is a hollow shaft 37 on the lower end whereof is a beveled gear 38 which meshes with a respective gear 18. On the upper end of this hollow shaft is a tube 39 carrying a cylindrical, or substantially cylindrical, brush 40.

From the drip pan a waste tube 41 extends to any convenient place for the disposal of 105 the soiled water. In Fig. 3 the device has been shown with bottles in position so that the operation thereof may be more clearly understood.

In using the device the bottles are placed 110 on the brushes, mouth downward, with their necks resting in the openings 15. The cold

2

water valve is at this time supposed to be wide open and the hot water valve closed. The operator then opens the valve 23 which admits cold water to the interior of the 5 bottles and then rotates the wheel 29 by means of the handle 30. This causes rapid rotation of the brushes in the bottles while, at the same time, the water is flowing down through said bottles. As the handle 30 is 10 rotated the cold water is gradually turned off and the hot water is turned on. Rotation of the handle is kept up until the hot water is turned on whereupon the rotation of the handle is reversed and rotation in the re- 15 verse direction kept up until the parts are in their normal condition. The bottles may be then readily removed and are thoroughly cleansed. By thus gradually changing the hot water to cold and reversing the opera- 20 tion boiling water can be used without danger of cracking the bottles or without the operator burning his fingers endeavoring to remove them from the case. It will be obvious that if desired the valves may 25 all be controlled by hand simply by leaving the arm 33 off of the pin 35 and removing the bar 27.

There has thus been provided a simple and efficient device of the kind described 30 and for the purpose specified.

Having thus described the invention, what is claimed as new, is:—

1. In a bottle washing machine, a series

of vertically arranged water supply pipes, a series of hollow shafts carried on said pipes, 35 brushes carried by said shafts, other shafts extending transversely of the first mentioned shafts, beveled gears connecting the hollow shaft and the last mentioned shaft, gearing connecting the last-mentioned shafts 40 with each other, means to actuate said gearing, valve controlled hot and cold water feed pipes connected to the first mentioned pipes, a drive shaft operated by said gearing actuating means, and means on said drive 45 shaft for opening and closing said valves.

2. In a bottle washing machine, a series of bearings, a series of revoluble brushes, water supply pipes extending through the centers of said brushes and journaled in 50 said bearings, a drive shaft, an operative connection between said brushes and the drive shaft to rotate all of said brushes simultaneously, hot and cold water feed pipes connected to said water supply pipes, 55 valves in the feed pipes, and an operative connection between the drive shaft, and said valves arranged to open one of said valves and close the other simultaneously.

In testimony whereof we hereunto affix 60 our signatures in presence of two witnesses.

FRANK BROOKS.
ISAAC K. HISEY.
